CORRECTIVE CHAIR

Barry L. Miller, Inglewood, Calif.

Application April 26, 1951, Serial No. 222,992

6 Claims. (Cl. 155—29)

This invention relates to a chair structure for the support, amelioration, and correction of the paralytic and spastic ravages of the motor nervous system, the same being particularly helpful to paraplegics and spastics. While the present chair may be used for aiding the training and coordination of unruly muscles of various paralytic conditions, both of adults and children, the invention, as herein disclosed, is more particularly adapted as a corrective aid for spastic children and it is an object of the present invention to provide such a chair structure.

Another object of the invention is to provide a chair of the character indicated, that is capable of substantially universal adjustment as to the angle of the seat and the relative positions of the back and foot support thereof, so that the chair may be adjusted to a wide range of positions between a flat reclining position and a "jack-knife" position in which the body is held at an acute angle to the thighs.

Another object of the invention is to provide a corrective chair in which the foot rest or support is independently adjustable and which, from any position of adjustment, automatically moves to accommodate itself to the normal or natural position of the feet according to whether the position of the child is a normal seated position or a reclining one.

Another object of the invention is to provide a chair, as indicated, that has outwardly tiltable arms to enable ready access for changing the clothes of the child while occupying the chair, said arms also being extensible so that the same may be adjusted to various support positions for the arms of the child.

A further object of the invention is to provide a chair of the present character in which the various components are extensible and contractible as desired so that the chair may be easily adjusted to the size of the child.

A further object is to provide in such a chair, restraining and corrective auxiliary devices for both the body and limbs of the child.

A still further object of the invention is to provide a chair structure that includes an independently usable stand which may be employed as a walking trainer as a further aid to the corrective education of the child.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a side elevational view of a chair embodying features according to the foregoing objects of the invention, the same being shown adjusted to hold a child in a normal seated position.

Fig. 2 is a similar view with parts broken away, showing the chair adjusted to hold a child in a reclining position.

Fig. 3 is a vertical sectional view as taken on line 3—3 of Fig. 1.

2

Fig. 4 is a front view of the foot rest of said chair, the view being seen in the direction of arrow 4 of Fig. 1.

Fig. 5 is an enlarged fragmentary sectional view on line 5—5 of Fig. 2.

Fig. 6 is an enlarged longitudinal sectional view on line 6—6 of Fig. 4.

Fig. 7 is a similarly enlarged fragmentary sectional view on line 7—7 of Fig. 1.

Fig. 8 is a fragmentary detailed sectional view of means employed to lock the adjustment of the chair components.

Fig. 9 is an enlarged cross-sectional view on line 9—9 of Fig. 8.

Fig. 10 is an enlarged front view, partly in section, of combined front retaining or restraining means and leg corrective means.

The chair that is illustrated comprises, generally, a mobile stand 15, an articulated chair 16 carried by said stand, jack means 17 interconnecting the stand and chair for adjusting the tilted position of the latter, and means 18 to lock the chair in adjusted position.

The stand 15 comprises side frames 19 integrally connected as by a cross member 20 of which more than the one shown may be provided. Said frames 19 are advantageously formed of metallic tubular elements and, in this case, are shown mounted on caster wheels 21. It will be evident that said stand may be employed as a "walker" by placing a child between frames 19 so that he may use rails 22 as hand supports and, thereby be maintained upright while propelling the stand along the floor.

Said rails 22 are provided with trunnions 23 for a pivot rod 24, the latter constituting a fulcrum on which chair 16 is adapted to be tilted.

The chair 16 comprises four major components—a seat 25, a back 26, a foot support 27, and arm rests 28.

The seat 25 comprises a metal frame formed of side bars 29 fixedly connected by transverse members 30, and a seat cushion 31 supported in the frame thus provided. The mentioned pivot rod 24 extends transversely at the rear of said frame. As shown, each bar 29 is provided with a rearward extension 32 having selective adjustment holes 33 or the like, and with a forward extension 34 having a pivot 35 on the forward end thereof.

The chair back 26 comprises a back support 36 and a head support 37, the latter being adjustable relative to the former, as shown in Fig. 2, by means of a bar 38 affixed to one support and slidable in suitable ways in the other, the adjustment being locked as by a wing nut 38a. While back support 36 may be generally flat or, at most, suitably transversely curved in the manner of chair backs, head support 37 has a considerable transverse curvature that results from the provision of side wings 39. These wings are provided for the primary purpose of limiting the position of a lolling head.

The back 26 is carried, at the bottom, by a U-shaped transverse frame 40 which is fulcrumed on pivot rod 24 on either side of seat 25.

Body restraining means 41 is provided on chair back support 36, the same, in this case, comprising a fabric band 42 carried at one end by a bracket 43 affixed to one side of said support, and separably connectable to a similar bracket on the opposite side. Such or similar restraining means 41 serves the purpose of either confining the body against undue movement or limiting the body against slipping laterally, depending on the tightness of adjustment of said means 41.

The foot support 27 comprises a frame 44 depending from seat frame 25 on pivots or hinges 45, a frame 46 within frame 44 and mounted on said hinges 45, a sliding frame 47 carried by frame 46, and a foot rest 48 carried by frame 47 and slidable therewith.

As best seen in Figs. 1, 2 and 4, frame 44 is U-shaped and, on the sides 49 thereof, carries locking knobs 50. Frame 46 comprises side bars 51 that are connected by transverse members 52, said frame being smaller than and, therefore, adapted to nest within frame 44. The frame sides 51 are provided with arcuate slotted rearwardly and upwardly directed extensions 43 which cooperate with locking knobs 50 to effect angular adjustment of frame 46 relative to frame 44, if such is desired. Fig. 1 shows one such adjustment, and Fig. 2 a some-

what smaller one. It will be realized that the angular adjustment may be such as to horizontally align frame 46 and seat 25 while frame 44 is in a pendent position.

Frame 47 comprises transversely spaced rectangular-sectioned tubes 54. A bracket 55 carried by each tube and a foot rest pad 56 transversely arranged between and connecting said brackets. Said brackets and pad constitute foot rest 48 and the same is adjustably carried by tubes 54 and locked thereto by means of bolts 57. Such adjustment may be made according to the leg length of the occupant of the seat, a slot 58 in each tube allowing for such adjustment. A calf-supporting pad 63a extends between tubes 54.

Frame 47 is slidably connected to frame 46 by means of shoulder screws 59, carried by frame 46, engaged in slots 60 formed in tubes 54. Sliding of frame 47 is effected through the medium of links 61 that connect the mentioned pivots 35 of the seat frame and tubes 54. Since pivots 35 and 45 are spaced, it will be clear that, as the foot support 27 is swung upwardly, frame 47 is projected relative to frame 46. Such projection can be seen in Fig. 2 by comparison to the relatively retracted position of frame 47 in Fig. 1. Since it is advisable that foot rest 48 support the legs so there is no binding or pressure on the inner side of the knee joints, the projection of said foot rest, when swung to the position of Fig. 2 independently of inclination of the chair back, obviates confining of the legs so that they may fully stretch. While the sliding adjustment thus effected is relatively small—in the nature of some two inches, the same is conducive to the comfort of the chair occupant and to corrective control of the lower limbs of said patient in all positions of the foot support relative to the seat.

The arm rests 28 are alike except that they are oppositely formed. Each arm rest comprises a metal frame 62 to which is affixed an upholstered pad 63 and which frame 62 carries an upwardly extensible pad 64. Figs. 1 and 2 respectively show partially extended and contracted positions which are locked by wing nuts 65 adjustably connecting frame 62 and slotted bars 66 affixed to and depending from pad 64.

The lower end of frame 62, on hinges 67, has slide bars 67a connected thereto. As best seen in Fig. 7, said bars extend into seats 68 provided in the lower side of the seat cushion 31, aligned openings 69 being provided in frame bars 29. From this structure, it will be clear that the arms rests are laterally extensible relative to seat 25 in addition to being vertically extensible.

Slide bars 67a are connected by a member 70 which mounts a hinged bolt 71, the same being adapted to extend through a slot 72 provided in frame 62. A wing nut 73 on said bolt serves to releasably lock frame 62 to member 70 to hold the arm rest erect. Release of bolts 71, on both sides, permits the arms to be outwardly swung, as shown by the dot-dash lines of Fig. 3.

The above-described adjustability of the arms permits the chair to accommodate persons of different size, provides for corrective elevational positioning of the arms, and gives improved access to the occupant for changing of clothing and for other purposes. Wing bolts 74 lock bars 67a to hold the arms in laterally adjusted position.

The seat 25, back 26 and foot support 27 are interconnected by oppositely disposed articulated parallelogram frames 75. Side bars 29 and 49 comprise two adjacent sides of said frames, and bars 76 and 77 comprise the remaining sides of said frames. Bars 76 comprise integral extensions of frame 40 and are slightly rearwardly offset therefrom as shown, to obviate the parallelogram frames locking when collapsed, as in Fig. 2. Bars 77 are connected by pivots 78 to the lower ends of bars 77 and by pivots 79 to comparable points of side bars 49.

It will be clear that the four pivots 24, 45, 78 and 79 will allow frames 75 to articulate so that when chair back 26 is swung on pivot 24, foot support 27 will swing through a corresponding arc, a downward and rearward movement of the chair back resulting in a forward and upward movement of the foot support and vice versa.

The position of Fig. 1 represents an intermediate seated position since the chair back 26 may be adjusted to incline toward the left to form an acute angle with seat 25, the "jackknife" position thus attained being desired for certain corrective retention of the chair occupant. The position of Fig. 2 represents an intermediate reclining position since the chair back may be further adjusted to

be horizontally aligned with the seat. In any position of the main chair components, the foot rest 48 may be separately adjusted relative to frame 44, both angularly on pivot 45 and longitudinally along frame 47.

It will be noted that bars 77 are each provided with a rearward extension 80 provided with adjustment holes 81. These holes, together with holes 33, allow for forward adjustment of the seat, and foot support relative to the seat back, as when adjusting the chair for a larger person.

A locking device 18 is provided to lock the adjusted positions of the back and foot support. Said device 18 is shown as an elongated rod 83 pivotally carried at 84 on a bridge piece 85 of frame 44 and rotationally mounted in a fitting 86, a handle 87 on the opposite end of said rod facilitating such rotation. Rod 83 extends through a sleeve 88 carried by an ear 89 on pivot rod 24. A one-way clutch 90 is embodied in sleeve 88 and serves to lock rod 83 to the sleeve when the handle 87 is rotated in a direction (clockwise in Fig. 9) to effect wedging of rod and sleeve by means of clutch 90. Reverse rotation of the handle releases the clutch and enables axial movement of the rod in the sleeve when the chair components are adjusted.

In addition to the above adjustments, jack means 17 is provided to tilt the chair bodily on its pivot 24 relative to frame 15. Said jack means is shown as a bracket 92 affixed to forward transverse member 30 of the seat frame, a jack rod 93 pivotally carried by said bracket, a suitable power-advantage gear box 94 through which rod 93 extends, a mount 95 pivotally connecting said gear box at 96 to frame 15, and an operating handle 97 for the mechanism within the gear box. Said mechanism is not detailed since the same is generally conventional for mechanical jack devices. It will be evident that the jack means 18 may be employed to adjust the angle of seat 25, all the parts connected to said seat bodily moving therewith.

As shown in Figs. 1, 3 and 10, a combined body retaining and leg correcting device 98 is provided, the same extending between arms 28. The device 98 comprises a length-adjustable bar 99 pivotally carried on a rotational pivot 100 at one end as on a bar 101 secured to the front edge of one arm pad 63. A similar bar 102 on the front edge of the other chair pad 63 releasably holds the other end of adjustable bar 99. The latter bar includes a channel member 103 on which is adjustably carried a pair of padded leg-engaging elements 104 which are curved substantially as shown to either engage the outer sides of the thighs or the inner sides, as suggested by the dot-dash line position of Fig. 10. The elements 104, having a variety of positions, may be adjusted to provide desired corrective restraint of the legs.

While not illustrated, the feet may be similarly restrained and held in corrective position as by means removably attached to foot rest 48. Spaced seats 105 are provided to mount such foot-correcting means.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described my invention, what is claimed and desired to be secured by Letters Patent is:

1. A corrective device of the character described, comprising a stand, an articulated chair pivotally carried by said stand and including a seat, a back, a pivoted foot support and a pair of arm rests, jack means to adjust and lock the tilted position of the chair relative to the stand, said latter means interconnecting the chair seat and stand, releasable locking means interconnecting the chair back and foot support to lock the adjustment of the chair back and foot support relative to the seat, the chair back comprising a body support and a winged head support, the foot support comprising an independently angularly adjustable foot rest, means interconnecting the foot rest and the seat to shift the former relative to the support during pivotal movement of the support, and the arm rests each comprising vertically extensible portions to vary the height thereof, the mentioned adjustments cooperating to confine the head, body and limbs of a spastic person occupying said seat.

2. A corrective device of the character described, comprising a stand, an articulated chair pivotally carried by said stand and including a seat, a back, a pivoted foot support and a pair of arm rests, jack means to adjust and lock the tilted position of the chair relative to the stand, said latter means interconnecting the chair seat and stand, releasable locking means interconnecting the chair back and foot support to lock the adjustment of the chair back and foot support relative to the seat, the chair back comprising a body support and a winged head support, an adjustable body-restraining band carried by the body support of the chair back, the foot support comprising an independently angularly adjustable foot rest, means interconnecting the foot rest and the seat to shift the former relative to the support during pivotal movement of the support, and the arm rests each comprising vertically extensible portions to vary the height thereof, the mentioned adjustments cooperating to confine the head, body and limbs of a spastic person occupying said seat.

3. A corrective device of the character described, comprising a stand, an articulated chair pivotally carried by said stand and including a seat, a back, a pivoted foot support and a pair of arm rests, jack means to adjust and lock the tilted position of the chair relative to the stand, said latter means interconnecting the chair seat and stand, releasable locking means interconnecting the chair back and foot support to lock the adjustment of the chair back and foot support relative to the seat, leg restraining and corrective means carried by the arm rests and extending across and above the front of the seat, the chair back comprising a body support and a winged head support, the foot support comprising an independently angularly adjustable foot rest, means interconnecting the foot rest and the seat to shift the former relative to the support during pivotal movement of the support, and the arm rests each comprising vertically extensible portions to vary the height thereof, the mentioned adjustments cooperating to confine the head, body and limbs of a spastic person occupying said seat.

4. In combination, a wheel-borne stand comprising spaced parallel frames and a cross rod extending between the upper portions of said frames, a chair seat disposed between the frames, said rod extending through the rear portion of said seat and constituting a pivot on which said seat is adapted to be angularly adjusted, a chair back pivotally mounted on said cross rod, an articulated and adjustable parallelogram frame connecting the chair back and the forward portion of the seat, a clutch-provided sleeve member pivotally carried by said cross rod, an elongated member extending through said sleeve mem-

ber and connected at one end to said articulated frame to articulate said frame and, thereby, adjust the angle of the chair back relative to the chair seat, the clutch of said sleeve locking the elongated member and the adjustment of the back, and a jack device interconnecting said stand and the forward portion of the seat to move the seat and back simultaneously and adjust the angle thereof relative to the frame by swinging movement on said cross bar.

5. The combination according to claim 4: an operating handle on the elongated member and an operating handle on the jack device, both said handles being disposed between the stand frames and directed from beneath the seat toward the rear of the stand.

6. An articulated chair comprising a seat, a back pivoted at the rear of said seat, a foot support pivoted at the front of said seat, means interconnecting the back and the foot support to cause pivotal movement of one in response to pivotal movement of the other relative to said seat, independently adjustable means between said interconnecting means and the foot support to vary the angle of the latter relative to the seat, said foot support comprising a frame depending from a hinge on the seat, a frame slideable on said hinged frame and provided with a foot rest, and a link interconnecting the slideable frame and the seat and pivotally connected to said seat forward of the hinge of the hinged frame, whereby pivotal movement of the hinged frame causes both pivotal and sliding movement of the frame having the foot rest.
